UNITED STATES PATENT OFFICE

GEORGE HENRY ELWELL, OF NEW HAVEN, CONNECTICUT, ASSIGNOR TO THE GREIST MANUFACTURING COMPANY, OF NEW HAVEN, CONNECTICUT, A CORPORATION OF CONNECTICUT

ELECTRIC SWITCH

Application filed October 10, 1927. Serial No. 225,198.

The invention relates to electric switches and especially to that class of reciprocating switches operatively thrown by means of push elements. In switches made adaptable for 5 use in connection with electric lamp sockets and like devices it is deemed important that provision be made therein for both a sudden make and break of the electrical contact upon the full operation of the reciprocating 10 means. It is therefore the object of this invention to provide an electric switch of that class having but one movable part and a torsion spring. Further objects will appear as the invention is described.

15 The following is the description of an embodiment of the invention, the construction of which within the scope of what hereinafter is claimed may be varied without departing from the spirit or modifying any of the advantages of the invention. Reference being had to the accompanying drawings (one sheet) the Figure 1 is an upright elevation of 20 an electric lamp socket, partly in cross-section, provided with the improved switch; Figure 2 is an upright elevation of the same 25 socket in a different position and the push element removed; Figure 3 is a top view of the supporting base of the lamp socket with the movable member mounted therein; and Figure 4 is a perspective view of the movable 30 member, and of the detached spring member and conductive spring element.

Referring more particularly to the drawings in which similar parts are similarly numbered the electric switch, while adapted for 35 association with any electrical device requiring a switch, is illustrated here in connection with an electric lamp socket in which the supporting base is the body of insulation 1 having the transverse cavity 2 within which are the pairs of spaced abutments 3 and 4 and the floor groove 5 communicating with the peripheral groove 6, as best illustrated by Figures 1 and 2. The movable member 7 comprises a frame stamped out from sheet metal 40 and carrying screwed or otherwise attached thereto the push elements 8 and 9 at either extremity and having an edge adapted to slide within the floor groove 5, the frame 45 being laterally supported by the ends of both

55 pairs of abutments 3 and 4. The frame of the movable member 7 is best illustrated by Figure 4 and there is illustrated as assuming the general form of the letter E lying upon its back with the extreme edge 10 of the 60 projecting center portion 11 twisted out of alignment with the main portion of the frame to the extent of approximately forty-five degrees. The metal stock is cut away along one full side of this edge 10 to form the 65 step 12. Fixed to the step side of the portion 11 is a part 13 of insulation material permanently attached thereto by means of a rivet, a thin metal lining 14 separating the portion 11 from the part 13 to complete the 70 metal groove 15. If the stock out of which the frame is stamped is of sufficient gauge to permit a substantial groove, like 15, to be made in the edge 10 this metal lining 14 may be omitted. The attached part 13 is so 75 constructed that it resembles in cross-section the letter U to form the insulation groove 16. The three parallel partitions 17, 18, and 19, are thus presented of which partition 17 is wholly of metal and extends at its forwardly 80 end farther than do the others. The partition 18 is of metal upon one side and of insulation material upon the other side, while the partition 19 is wholly of insulation material and extends at its rearwardly end farther 85 than do the others. Suspended from the washer 20 of insulation material is a torsion spring 21 fixed thereto by the same eyelet by which the center lamp-contact is secured to the reversed side of the washer as illustrated 90 by Figures 1 and 2. This spring 21 has a normal at-rest position in the center of its arc of forced vibration in a plane of movement at right angles to the edge 10 and its free extremity is permanently slightly twisted to normally lie out of the general plane of the spring proper and is thus adapted to engage within either of the grooves 15 or 16 wiping both sides of each groove or lying 95 against either of the extensions of the partitions 17 or 19 upon the reciprocal operation of the movable member 7 to either full position, the Figures 1 and 2, illustrating the free extremity of the torsion spring 21 in engagement with the extension of the par- 100

tition of insulation 19. Lying flatly under the movable member 7 and within the floor groove 5 is the metal strip 22 bent at right-angles adjacent the periphery of the body 1 to assume a wider proportion within the peripheral groove 6 and to there form the binding-post 23 of the center lamp-contact, the binding-post (not illustrated) of the screw-shell being of any desired form or construction.

From the foregoing description it will be obvious that when the torsion spring 21 is held as illustrated in the Figures 1 and 2, it is detained in a deflected position of forced vibration. As the push element 9 is inwardly operated the movable member 7, advancing in an oblique plane to that of the arc of vibration of the torsion spring 21, permits the spring extremity to seek its normal at-rest position midway within the groove 16 of insulation and then, upon the full operation of the movable member 7, the spring extremity is forced to continue through the groove 16 to an extreme position in its arc of vibration in the opposite direction to that illustrated in the drawings until the spring extremity is permitted to snap out of the groove 16 and against the extension of the metal partition 17 as the spring extremity thus partially returns to its at-rest position. The electric circuit is thereby closed and remains closed as long as the spring extremity engages the extension of partition 17 or within the metal groove 15. In reversing the action of the electric switch the inwardly push of the element 8 permits the spring extremity to engage through to midway of the length of the groove 15 where the spring extremity finds its at-rest position, but upon the full operation of the push element 8 the spring extremity is made to continue its engagement throughout the groove 15, being thereby forced to assume its extreme position in its arc of vibration in the direction illustrated in the drawing until the spring extremity is permitted to snap out of the groove 15 and against the extension of the insulation material of the partition 19. The electric circuit is thereby opened to remain open as long as the spring extremity engages the extension of partition 19 or within the groove 16. It will be noticed that as the spring extremity is engaged within the groove 15 its tendency, by virtue of its continuously seeking its at-rest position, is to bear against one side of the metal groove to a point midway therein and then to bear against the opposite side of the same groove from the midway point throughout the remaining course of the groove. To permit this transfer at any point within the groove would interrupt the much desired continuity of a closed circuit until the spring extremity arrives at its snapping position as before explained. Therefore the spring extremity, being permanently formed

with a slight twist out of the general plane of the spring proper, is made to enter the groove 15 only upon a forced twist of the torsion spring thus insuring such a relative position of the spring extremity within the groove that it provides a wiping contact of both sides throughout the course of the entire groove regardless as to its bearing tendency mentioned above. While the spring extremity engages the groove 16 in like manner, yet its engagement there is of no greater importance than to be maintained within the groove until it arrives at its snapping position to close the circuit as above explained. An exceedingly simple and most effective electric switch is thus provided. Its operation is easy because the spring resistance is so slight and yet, when the electric circuit has been once closed or opened, no jar or other disturbance short of a manual operation of a push element can open or close the circuit. The persistent tendency of the spring extremity to seek an at-rest position prevents a jar from operating the switch beyond such a point wherein the spring extremity has found its at-rest position midway within either groove.

What I claim is:

1. An electric switch comprising a movable member mounted upon a supporting base, a conductive spring fixed to the base and having an extremity adapted for an intermediate at-rest position and for a forced arc of movement in both directions obliquely across the path of the movable member, and conductive and non-conductive means carried by the movable member and engaged by the spring extremity to move the extremity into and out of contact with the conductive means.

2. An electric switch comprising a reciprocating operating member mounted upon a supporting base, a conductive spring fixed to the base and having an extremity adapted for an intermediate at-rest position and for a forced arc of movement in both directions obliquely across the path of the reciprocating member, and rigid conductive and non-conductive means provided by the reciprocating member and carrying the spring extremity into and out of contact with the conductive means as the reciprocating member is manually operated in opposite directions.

3. An electric switch comprising a longitudinally movable member within a supporting base, the member carrying parallel grooves positioned obliquely to its path of movement, each groove having an outside wall extending beyond the groove, each extending wall extending in opposite directions, and a swinging spring device fixed at one end to the base and its other end being adapted for a normal at-rest position intermediate its arc of movement and within one of the grooves, the spring and only one of

the grooves with its extending wall being conductive.

4. An electric switch comprising an insulation base having a cavity, a reciprocating operating member movably mounted within the cavity, parallel grooves carried by, and positioned obliquely to the path of movement of, the reciprocating member, each groove having an outside wall extending beyond the groove, each extended wall extending in opposite directions, and a spring secured to the base and having a suspended terminal adapted for a normal at-rest position intermediate its arc of movement and within one of the grooves, the spring and only one of the grooves with its extending wall being conductive.

5. An electric switch comprising an insulation base having a cavity, a reciprocating operating member movably mounted within the cavity, parallel grooves carried by, and positioned obliquely to the path of movement of, the reciprocating member, each groove having an outside wall extending beyond the groove, each extended wall extending in opposite directions, and a spring secured to the base and having a suspended and twisted terminal adapted for a normal at-rest position intermediate its arc of movement and within one of the grooves for engagement with both walls of the groove, the spring and only one of the grooves being conductive.
